UNITED STATES PATENT OFFICE.

JAMES A. BUREN, OF TACOMA, WASHINGTON.

TOBACCO CAN.

Application filed April 9, 1923. Serial No. 630,890.

To all whom it may concern:

Be it known that I, JAMES A. BUREN, a citizen of the United States, residing at Tacoma, in the county of Pierce and State 5 of Washington, have invented certain new and useful Improvements in Tobacco Cans; and I do declare the following to be a full, clear, and exact description of the invention, such as will enable others skilled in the art 10 to which it appertains to make and use the same.

My invention relates to improvements in tobacco cans and has for its object to provide an extremely simple and inexpensive 15 means whereby a vertically adjustable bottom for the can may be held in any position to which it is moved, as the contents of the box are used.

With the foregoing in view, the invention 20 resides in the novel subject matter herein-after described and claimed, the description being supplemented by the accompany-ing drawing.

Figure 1 is a vertical sectional view of a 25 tobacco can constructed in accordance with my invention.

Figure 2 is an edge elevation partly in 30 vertical section.

Figure 3 is a horizontal sectional view as 35 indicated by line 3—3 of Fig. 1.

Figure 4 is an enlarged vertical section on line 4—4 of Fig. 3.

Figure 5 is an end elevation of the ad-justable bottom.

In the drawings above briefly described, 40 the numeral 1 designates an upright con-tinuous side wall having the usual or any preferred cover 2, the edge portions of this wall being stamped outwardly at intervals to provide them with series of vertically spaced convolutions forming internal re-cesses 3. A sheet metal bottom 4 is received 45 within the wall 1 and has its edge portion bent downwardly to form a vertical flange 5 which contacts slidably with said wall. The portions of the flange 5 at opposite ends of the bottom 4, are formed with opposed

50 pairs of vertical slits 6 cut upwardly from the lower edge of said flange and which preferably extend somewhat into the ends of the bottom proper, the metal 7 between the pairs of slits 6, being outwardly bowed to form resilient tongues 7 for engagement with the internal recesses 3, thereby holding the bottom 4 in any position to which it 55 may be adjusted. It will be obvious that as the bottom is moved upwardly, the tongues 7 will spring inwardly and will snap under their own resiliency, into engagement with the next set of recesses.

60 By the use of the invention, it will be seen that as the contents of the can are used, the bottom and the usual oiled paper sack which contains the tobacco, within the wall 1, may be raised, giving easy access to the 65 tobacco for loosening it with the finger.

As excellent results may be obtained from the details disclosed, these details are preferably followed, but within the scope of the invention as claimed, minor changes may of 70 course be made and it is obvious that my invention is not restricted to use upon tobacco cans, as containers of other characters may be constructed in accordance therewith.

I claim:

75 A container having in its walls opposed vertically disposed convolutions forming spaced internal recesses, a bottom arranged for vertical sliding movement in said con-tainer, said bottom having a downwardly 80 projecting flange provided with oppositely disposed parallel slits extending upwardly from the lower edge of the flange and into said bottom, and tongues formed by bend-ing the metal between said parallel slits, out-wardly and then inwardly for close resilient 85 engagement with the recesses formed by the convolutions in the walls of the container when the bottom is pushed upwardly there-in.

90 In testimony whereof I have hereunto af-fixed my signature.

JAMES A. BUREN.
